UNITED STATES PATENT OFFICE.

JOHN EDWARD GLOEKLER, OF PITTSBURGH, PENNSYLVANIA.

SUPPORTING MEANS FOR HORIZONTALLY-DISPOSED SURFACES.

Application filed October 18, 1924. Serial No. 744,436.

Among the objects which I have in view is the provision of improved means for supporting working surfaces or members, such as table-tops and the like, in spaced relation 5 to the floor or ground.

I accomplish this object by means of my improved corner bracket and leg-construction.

My improved corner bracket is preferably 10 an integral casting comprised of a horizontal platform upon which the corner of the table-top or other horizontal surface rests, an angular flange extending upwardly from said platform and inclosing the vertical surfaces 15 of the table-top adjacent to its corner and attached thereto, as by bolts, screws or rivets, and a socket depending from the platform. The leg-member has its upper end inserted into and secured in the socket, 20 means being provided for adjusting the insertion of the leg-member in the socket to regulate the length of the leg. The socket is preferably internally threaded and the upper end of the leg-member screwed 25 therein.

In the accompanying drawings, Fig. 1 is a broken perspective of a table to which my invention is applied; Fig. 2 is a perspective of one of the corner brackets shown reversed 30 from its position in Fig. 1; Fig. 3 is a perspective of one of the shelf brackets, and Fig. 4 is an elevation of the same attached to the shelf, the latter being vertically sectioned for the sake of clearness.

35 The following is a detailed description of the drawings.

A represents the table-top, such for instance as a steam table having vertical sides 1 and ends 2 which merge to form the corners 40 of the table top.

B represents one of the corner brackets, which is preferably a casting, and is of the following construction. 3 is a horizontal platform upon which the corner of the table-top rests, and 4 is an upwardly extending, angular flange which snugly fits around and incloses the corner formed by the side and end of the table-top. The flange 4 is provided with a plurality of properly spaced holes 5 which register with holes in the table-top for the insertion of bolts, screws or rivets 6, to firmly secure the flange 4 to the table-top.

55 The underside of the platform 3 is provided with a depending socket 7 in which the upper end of the leg member C is in-

serted and secured. The leg member may conveniently be a length of pipe or rod.

I prefer to make the degree of the leg member's insertion in the socket adjustable 60 to provide for regulating the height at which the table-top is to be supported and also to compensate for floor irregularities. Thus I prefer to internally thread the socket 7 and externally thread the upper end of the leg member and screw the same to the desired degree into the socket. To give a better footing for the leg member and provide for additional adjustment I screw onto the lower end of the leg member a foot member D 70 which may be readily adjusted to cause the table to stand solidly.

It is evident that the table-top is firmly and rigidly supported by the use of my invention.

E represents an intermediate shelf which is supported in place through its attachment to the leg members C by means of my improved shelf-brackets F.

The shelf-brackets are preferably integral 80 castings, and are of the following construction. 8 and 9 represent horizontal arms extending in rectangular relation to each other so as to fit about the corner portion of the shelf E. Said arms are provided with properly spaced holes 10 which register with similar holes in the depending perimetral flanges 11 of the shelf, and bolts, screws or rivets 12 are introduced into said holes to firmly secure the brackets to the shelf. The 90 arms 8 and 9 are provided with inwardly turned bottom flanges 8^a and 9^a upon which the shelf rests. 13 is a split collar, integral with the arms 8 and 9 and positioned against the exterior of one of the arms, as 8 in the 95 drawings. The free end of the collar 13 is provided with a tongue 14 which is parallel with the arm 8. The collar 13 is slipped over the leg member C and is positioned thereon to provide the desired shelf-elevation, and the collar is then tightened to clamp it rigidly and fixedly on the leg member.

The tongue 14 is provided with a bolt hole registering with the inner-bolt hole 10 in the arm 8 so that the bolt which is inserted through that hole in the arm to attach the shelf to the bracket may also be used to clamp the bracket to the leg member.

It is evident that the shelf is firmly fixed on and supported by the leg members. It 110 is further evident that by loosening the proper bolts, the split collars may be loosened

on the leg-members and the shelf shifted to a lower or higher position, as may be desired, and then fixed in such position by retightening the bolts.

5 My invention is inexpensive and durable, and when applied to the support of tabletops, shelves and the like presents an attractive appearance.

What I desire to claim is:—

10 A bracket adapted to snugly engage the aprons at the corner of a table or the like comprising a triangular shape platform hav-

ing two upstanding flanges thereon meeting at the apex of the platform and an open ended leg socket depending from the lower side of the platform, the inner sides of the upstanding flanges being tangent to the inner edge of the leg socket whereby said aprons constitute a stop for the leg when inserted in said socket.

15 Signed at Pittsburgh, Pa., this 13th day of October, 1924.

JOHN EDWARD GLOEKLER.
